UNITED STATES PATENT OFFICE.

ELLSWORTH W. AUSTIN, OF PLYMOUTH, CONNECTICUT.

VAPORIZING ATTACHMENT FOR EXPLOSIVE-ENGINES.

1,321,079.

Specification of Letters Patent. Patented Nov. 11, 1919.

Application filed February 28, 1919. Serial No. 279,814.

To all whom it may concern:

Be it known that I, ELLSWORTH W. AUSTIN, a citizen of the United States, and a resident of Plymouth, in the county of Litchfield and State of Connecticut, have invented certain new and useful Improvements in Vaporizing Attachments for Explosive-Engines, which improvements are full set forth in the following specification.

This invention relates to improvements in devices of that class available for enhancing the vaporization of the power medium or fluid inflowing to the interior of the cylinder or cylinders of a so-called hydro-carbon or explosive engine, and essentially to facilitate the starting and increase the otherwise normal efficiency thereof, such devices being well-designated vaporizing attachments for explosive engines.

The object of this invention is to provide a vaporizing attachment of the character aforesaid which shall be simple and inexpensive as regards its construction; durable, efficient and reliable in practical service; convenient in its application to practical purposes; and which shall possess certain well-defined advantages over prior analogous constructions.

The invention consists in the combinations, details and parts whereby, together with the novel disposition and relative arrangement of said parts, the attainment of the foregoing object is rendered practicable, all of which will be hereinafter more specifically referred to and set forth in the claims hereto appended.

The invention is clearly illustrated in the accompanying drawing, wherein:

Figure 1 is a side elevation of a vaporizing attachment for explosive engines embodying my said improvements, an explosive engine being shown also in side elevation conjunctively therewith, to better illustrate the practical application of the device.

Fig. 2 is a top plan view of the attachment, detached, the scale being materially enlarged.

Fig. 3 is an end view thereof, detached, the scale conforming to that of Fig. 2.

Fig. 4 is a section, mainly horizontal, of the attachment detached, as along the irregular dotted line $x-x$ of Fig. 3 and conforming thereto in scale.

Fig. 5 is a central, transverse section of the attachment, detached, as along the dotted line $y-y$ of Fig. 2, and conforming thereto in scale.

Fig. 6 is a view similar to Fig. 5, showing the heat-diffusing stopper substituted for the air-inlet stopper, made use of, the scale being unchanged.

Fig. 7 is a detail view showing, partially in perspective and partially in central, longitudinal section and detached, the air-inlet stopper made use of, the scale being still further enlarged.

Having reference to the accompanying drawing, wherein similar reference-characters denote like parts throughout the several views, and wherein, to facilitate the description of my improved vaporizing attachment in its application to a so-called hydro-carbon or explosive engine, A denotes generally such engine, B its manifold and C its carbureter, I, in carrying out my present invention, make use of a joint-block 2, having a central power-mixture passage 2', said joint-block being pierced, radially by preference, for the formation of a stopper-receiving opening 2'', at a suitable point or segment thereof circumferentially of the passage 2' and intersecting and communicating therewith, and preferably for the formation of a similar opening 3, at that point or segment of the joint-block situated diametrically opposite the opening 2'' and aligning axially therewith, the opening 3 being duly threaded interiorly for the reception of a suitable exteriorly threaded plug 3', which serves as a closure for the opening 3, and which may be readily displaced for facilitating the cleansing, if need be, of the interior of the joint-block aforesaid, the latter constituting a segment of the fluid feed-conduit made use of, and being situated, in this instance, intermediate the carbureter outlet 3'', fitted with an annular flange 4, and the manifold intake 4', having an annular flange 4'', and being there firmly held, as through the medium of the bolts 5, 5', piercing the flanges 4, 4'', respectively, with the joint-block aforesaid positioned therebetween, and fitted, respectively, at their threaded advance ends with suitable fastening nuts 5'', 5'', whereby the adjoining parts may be drawn snugly together, all as clearly illustrated in the accompanying drawing.

The opening 2'' is formed tapering from its mouth inwardly, to the end that a suitable stopper, having a corresponding taper,

may be snugly seated therein and serve as a closure therefor.

In this connection, and to better encompass the purposes of my present invention, I 5 contemplate providing a plurality of stoppers 6, 6', correspondingly tapered and adapted to be interchangeably availed of as closures for the opening 2", the same being suitably tapered, respectively, to this end, 10 and each, accordingly, being a counterpart of the other as regards its tapered form and, hence, its adaptability to serve as a closure for said opening.

The stopper 6 is preferably provided with 15 an eye 6", to facilitate the attachment thereof to any suitable object, as the lug 7, and as through the medium of a suitable flexible connection, as the chain 7", whereby misplacement of the stopper now under consideration is obviated, lug 7, being, by preference, provided with a suitable hole 7", to receive and retain said stopper when not in use.

Stopper 6 is further provided near its diametrically enlarged end with a lateral air-intake port 7", from which leads inwardly an initial air-inlet 6", terminating at and in communication with an intermediate, central, longitudinal air-inlet 8, of a given diameter, said air-inlet 8 in turn terminating at and in communication with a final air-inlet 8', the latter being diametrically enlarged to form a valve-seat 8", to which is yieldingly and snugly held, under normal 35 conditions, and as through the medium of a spiral spring 8", a cup-valve 9, said cup-valve receiving and housing the adjacent end of the spring 8", and the latter occupying the final air-inlet 8' and abutting end- 40 wise at its opposite end against the radially inturned flange 9', preferably interrupted as shown, at the inner end of the stopper 6, and being duly confined, through the medium of said flange, within the air-inlet 8', 45 as will be clearly noted on reference to the drawing.

The stopper 6' has a general tapered form conforming, particularly at its diametrically enlarged end-portion, to that of the stopper 6, and to such an extent is a counterpart of the latter. Stopper 6', however, is, by preference, more elongated than stopper 6, and while being a counterpart of the latter in its adaptability to serve as a closure for the opening 2", the same is formed solid as shown.

I contemplate providing stopper 6" with a suitable hand-piece 9", the latter being, by preference, provided with an eye 9"" at 60 its free end.

In practice, and for priming or starting purposes in connection with explosive engines of practically all types, it is desirable and not merely essential in low atmospheric

temperatures, that the inflowing power-mixture be subjected to a markedly high degree of heat, and accordingly expanded or vaporized in advance of its reaching the interior of the cylinder or cylinders of the engine, and I accomplish this important end, 65 in engines to which my improved vaporizer may be applied, by duly preheating, at any available source of heat, say, stopper 6', and thereafter inserting the same snugly into the opening 2", this more elongated, and incidentally solid form of stopper, which then traverses diametrically the intake passage 2' and has a substantial, heat-radiating surface, diffuses its contained heat in a manner to markedly increase the temperature of the 80 power-mixture, as the same approaches in volume and inflows from said stopper, thereby well preheating and hence vaporizing such inflowing power-mixture and facilitating the priming or starting of the engine 85 accordingly.

The engine having been gotten well in motion in the manner above stated, stopper 6, say, may now be interchanged for the stopper 6', and accordingly snugly seated 90 within the opening 2", to there serve both as a more permanent closure for the opening 2" and incidentally as a controllable auxiliary air-inlet to be shortly hereinafter explained; and in this connection, and while 95 affording materially less heat-radiating surface, stopper 6 may be measurably preheated, as defined in conjunction with stopper 6' and utilized, accordingly, as a substitute for the latter, when preheated, and for 100 measurably performing the heat-diffusing function thereof, as hereinbefore explained, the respective stoppers 6, 6' being again, in this respect, counterparts each of the other, as will be apparent.

With the engine underway as stated, it becomes not rare-desirable, for speed-up and other efficiency-enhancing purposes, attainable through increased vaporization of the power-mixture inflowing from the carburetor C, that the power-mixture availed of be controllably surcharged with auxiliary volumes of atmospheric air, and I attain this last-named end by providing stopper 6, say, with a suitable general air-inlet such as 110 formed by the intercommunicating constituent air-inlets 6", 8, 8', having a lateral intake-port 7", the inflow of such auxiliary volumes of atmospheric air, by way of the general air-inlet aforesigned, and into the 115 intake-passage 2', for its surcharging effect there on the inflowing power-mixture, being automatically induced under the suction of the engine in operation, cup-valve 9 being thereunder caused to recede from its seat 8" 120 against the tendency of the spring 8", thus opening the general air-inlet, aforesigned, and port 7" being open to the atmosphere.

To the end that the inflowing air may be definitely controlled as to volume, I provide a shut-off shoulder 10, the formation of which may be effected by a proper distribution of the material of the joint-block 2, as clearly indicated in Figs. 5 and 6 of the drawing; and in this connection, when stopper 6, say, occupies its position shown in Fig. 5, with its intake-port 7" out of registration with the shoulder 10, outside air is free to move in volume into the intake-opening 2', by way of the general air-inlet aforementioned and its port 7", valve 9 being open, while such in-moving volume of air may be diminished or controlled by duly rotating the stopper last-named on its own longitudinal axis, and proportionally to the extent to which the port 7" may, through rotation of said stopper as stated, be brought into closing registry with the shoulder 10, as will be clearly understood.

When either of the stoppers aforementioned is in service as a closure for the opening 2', the other, to obviate its misplacement, may conveniently occupy the hole 7''' formed in lug 7.

The operation of my improved vaporizing attachment for explosive engines should be apparent from the foregoing description thereof; and it will be seen that the same is well adapted for the purposes for which it is intended, and further that the same may be modified to a considerable extent, particularly as regards the specific form of the heatable stopper for the opening 2" made use of, and other minor details of the general construction, without material departure from the spirit and principle of my invention as coming within the scope of the claims hereto appended.

I claim:

1. A device of the class herein described comprising a joint-block having a longitudinal power-mixture passage and a stopper-receiving opening, and a preheated stopper, the latter displaceably closing said opening and adapted, through diffusion of more or less of its contained heat, to raise materially the temperature of the contents of the passage aforementioned.

2. A device of the class herein described comprising a joint-block having a longitudinal power-mixture passage and a stopper-receiving opening, and a preheated stopper, the latter displaceably closing said opening and intersecting more or less the power-mixture passage aforementioned.

3. A device of the class herein described comprising a joint-block having a longitudinal power-mixture passage, a stopper-receiving opening and a plug-receiving opening, said stopper-receiving opening and plug-receiving opening being arranged in diametric alinement relatively to the power-

mixture passage aforementioned and each communicating therewith; a plug displaceably closing said plug-receiving opening, and a stopper, the latter displaceably closing said stopper-receiving opening.

4. A device of the class herein described comprising a joint-block having a longitudinal power-mixture passage, a stopper-receiving opening and a plug-receiving opening, said stopper-receiving opening and plug-receiving opening being arranged in diametric alinement relatively to the power-mixture passage aforementioned and each communicating therewith; a plug displaceably closing said plug-receiving opening, and a stopper, the latter displaceably closing said stopper-receiving opening, traversing said power-mixture passage, and whose tip-portion measurably occupies said plug-receiving opening, in advance of the plug therein.

5. A device of the class herein described comprising a joint-block having a longitudinal power-mixture passage and an inwardly tapered stopper-receiving opening, said opening communicating with said passage, and a stopper, the latter tapered to snugly seat within, and displaceably closing, said opening.

6. A device of the class herein described comprising a joint-block having a stopper-receiving opening, a stopper displaceably closing said opening and affording an attaching eye, and a flexible connection, the latter linked or otherwise suitably conjoined, at one of its ends, with said attaching eye.

7. A device of the class herein described comprising a joint-block having a stopper-receiving opening and a lug projecting therefrom, a stopper adapted to displaceably close said stopper-receiving opening when duly seated therein and affording an attaching eye, and a flexible connection, the latter linked or otherwise suitably conjoined, at one of its ends, with said attaching eye, and at its opposite end with the lug aforementioned.

8. A device of the class herein described comprising a joint-block having a stopper-receiving opening and a lug projecting therefrom, said lug having a stopper-receiving hole formed therethrough, and a stopper, the latter adapted to displaceably close said stopper-receiving opening when snugly seated therein, and further adapted, when displaced from said stopper-receiving opening, to be inserted endwise and retained within the stopper-receiving hole aforementioned formed in said lug.

9. A device of the class herein described comprising a joint-block having a longitudinal power-mixture passage, a stopper-receiving opening establishing communication between said passage and the outside air, and a shut-off shoulder, at the mouth of said

stopper-receiving opening, and a stopper, the latter displaceably closing said stopper-receiving opening, having a valve-controlled air-inlet fitted with a lateral intake-port, 5 and being rotatable on its own longitudinal axis to bring the said intake-port more or

less into closing registry with the shoulder aforesaid, whereby the admission, under suction, of outside air to and into the power-mixture passage aforesaid may be controlled as to volume. 10

ELLSWORTH W. AUSTIN.
